US0D1095506S

(12) **United States Design Patent** (10) **Patent No.:** **US D1,095,506 S**
Yang (45) **Date of Patent:** **** Sep. 30, 2025**

(54) **GATEWAY**

(71) Applicant: **SHENZHEN KERUI SMART TECHNOLOGY CO., LTD.**, Shenzhen (CN)

(72) Inventor: **Jianhui Yang**, Shenzhen (CN)

(73) Assignee: **SHENZHEN KERUI SMART TECHNOLOGY CO., LTD.**, Shenzhen (CN)

(**) Term: **15 Years**

(21) Appl. No.: **29/962,125**

(22) Filed: **Sep. 10, 2024**

(51) **LOC (15) Cl.** **14-02**

(52) **U.S. Cl.**

USPC **D14/356**; D14/242

(58) **Field of Classification Search**

USPC D14/135, 140, 140.1–140.8, 155–159, D14/160–174, 188–199, 200–203, D14/203.1–203.8, 204–216, 217–222, D14/240–244, 256–257, 265, 300–302, D14/348–349, 356–358, 432–434, 439, D14/496–497

CPC H04L 12/00; H03K 17/00; H04W 88/00; H04W 88/005; H04W 88/02; H04W 88/08; H04W 88/085; H04W 88/10; H04W 88/12; H04W 88/14

(57) **CLAIM**

The ornamental design for a gateway as shown and described.

DESCRIPTION

FIG. 1 is a front, left and top perspective view of a gateway, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of detail 9 in FIG. 1.

The dashed broken lines depict portions of the gateway that form no part of the claimed design.

The dot-dash broken lines in FIGS. 1 and 9 depict the boundaries of the enlargements and form no part of the claimed design.

1 Claim, 9 Drawing Sheets
